(57) CLAIM

The ornamental design for a combined picture frame and message recorder, as shown and described.

DESCRIPTION

FIG. 1 is a front elevational view of the combined picture frame and message recorder of the present invention;

FIG. 2 is a rear elevational view of the combined picture frame and message recorder of FIG. 1;

FIG. 3 is a left side elevational view of the combined picture frame and message recorder of FIG. 1;

FIG. 4 is a right side elevational view of the combined picture frame and message recorder of FIG. 1;

FIG. 5 is a top plan view of the combined picture frame and message recorder of FIG. 1, the bottom view being a mirror image thereof;

FIG. 6 is a top, front, left side perspective view of the combined picture frame and message recorder of FIG. 1;

FIG. 7 is a front elevational view of an alternate embodiment of FIG. 1 of the combined picture frame and message recorder; and,

FIG. 8 is a left side elevational view of FIG. 7 of the combined picture frame and message recorder.

The surface(s) or portion(s) of the article not shown in the drawing or described in the specification form(s) no part of the claimed design.
